Att'y.

UNITED STATES PATENT OFFICE.

WILLIAM R. BROUH, OF EAST ORANGE, NEW JERSEY, ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed May 13, 1922. Serial No. 560,648.

To all whom it may concern:

Be it known that I, WILLIAM R. BROUH, a citizen of the United States, residing at East Orange, in the county of Essex, State 5 of New Jersey, have invented certain new and useful Improvements in Electron-Discharge Devices, of which the following is a full, clear, concise, and exact description.

This invention relates to electron dis- 10 charge devices and especially to a cooling system therefor.

Certain types of high power electron dis- 15 charge devices comprise a metallic cup-shaped member which forms a portion of the enclosing vessel and acts as the anode of the device. In the operation of these devices, it is customary to enclose the metallic portion with a jacket into which a cooling fluid is introduced to remove from 20 the anode the heat developed in it during the operation of the device.

An object of this invention is to effect a fluid-tight connection between the water jacket and the metallic portion of the device.

25 An additional object of the invention is a simple and efficient means for attaching an electron discharge device to the water jacket.

Other objects and novel features of this invention will be apparent from the following specification and accompanying drawing wherein Fig. 1 is a sectional view partially 30 in elevation of an embodiment of the invention, and Fig. 2 is a plan view thereof.

A water jacket 10 is provided with inlet 35 and outlet ports 11 and 12 and at its upper

end has an inwardly projecting flange 13 in which is provided a screw threaded aperture.

Arranged within the water jacket is the anode 14 of an electron discharge device 15. 40 On the anode 15 adjacent its upper end is brazed or otherwise permanently attached the collar 16, a portion of which is screw-threaded to engage with the threads of the flange 13. The upper portion of the collar 45 16 is formed in the shape of a hexagonal nut. Interposed between the upper portion of the collar and the flange 13 is a gasket 17.

The device 15 with the collar 16 attached thereto is screwed into the flange 13 and tightened against the gasket 17 until a water-tight connection is obtained. During the operation of the device, water is caused to circulate through the jacket from the inlet 50 11 to the outlet 12 and serves to maintain 55 the anode 14 at a sufficiently low temperature to insure proper operation of the device.

The invention claimed is:

In combination, a water jacket having an inwardly projecting screw-threaded annular 60 flange, an electron discharge device comprising an envelope having a metal portion, and a screw-threaded collar carried by said metal portion to cooperate with said flange to produce a water-tight connection between 65 said water jacket and said metal portion.

In witness whereof, I hereunto subscribe my name this 10th day of May A. D., 1922.

WILLIAM R. BROUH.
